OSCILLATION GENERATOR OF THE REFLEX
TYPEWilliam W. Rigrod, Bloomfield, N. J., assignor to
Westinghouse Electric Corporation, East Pitts-
burgh, Pa., a corporation of Pennsylvania

Application March 9, 1943, Serial No. 478,560

7 Claims. (Cl. 315—5)

1

This invention relates to velocity-modulated generators and reflector electrodes for electricity of ultra-high frequency, and more particularly to a special construction of reflector electrodes to facilitate the focusing of electron beams.

The primary object of my invention, generally considered, is to provide an improved means for adjusting the transit time and controlling the focusing of electron beams, especially in velocity-modulated generators for electricity of ultra-high frequency, of the type generally designated as reflex Klystrons.

Another object of my invention is to provide an improved velocity-modulated tube, and especially one of the reflex Klystron type, whereby the electron transit time and the focusing of the electron beam may be more readily controlled.

A further object of my invention is to provide means in a reflex Klystron for focusing the returned electron beam by merely controlling the potential of an inner element or cylinder disposed between a reflector electrode and a resonant-cavity member.

A still further object of my invention is to provide an improved reflex Klystron in which the electron beam may be controlled without changing the voltage of the reflector electrode.

Other objects and advantages of the invention, relating to the particular arrangement and construction of the various parts, will become apparent as the description proceeds.

Referring to the drawing illustrating the invention:

Fig. 1 is a fragmentary axial sectional view of a device, of the type generally designated as a reflex Klystron, for generating electricity of ultra-high frequency.

Fig. 2 is a transverse sectional view on the line II—II of Fig. 1, in the direction of the arrows.

Fig. 3 is a fragmentary axial sectional view of a modified reflector electrode, associated focusing member, and part of the associated resonant cavity member, as shown in Fig. 1.

Figs. 4 and 5 are views corresponding to Fig. 3, but showing modifications.

Fig. 6 is a view corresponding to Fig. 3, but showing a modification in which the focusing element between the reflector electrode and resonant cavity member is dispensed with, the shape

of the reflector alone being relied on for accomplishing the desired purpose.

In the reflex Klystron, electrons in the form of a beam, after being "bunched" by passing axially through an electric field oscillating at ultra-high frequency, enter a region of electric field, which retards them until they come to rest and reverse their direction of motion. During this round trip, the differential accelerations and retardations superimposed on their motions in the "bunching" process, results in the formation of electron packets which, after reflection, re-traverse the ultra-high frequency field at times when that field most strongly opposes their motion. By suffering deceleration under the action of this field, the electron packets or "bunches" give up energy thereto and so sustain its oscillations.

In order to convert the greatest fraction of the electrons' kinetic energy into oscillating electric field energy, the direct retarding field, which effects reversal of the electrons' direction, must be designed to:

(1) Focus the returning electron beam into the region of strongest oscillating field, and

(2) Retard the electrons at the proper rate so that the "bunches" are in the optimum phase relation with respect to said field.

In prior forms of the Klystron, a single reflector electrode has been used to perform both of the above functions, by varying the voltage (E_s) of the resonant cavity member, cavity resonator, or shell and the reflector voltage (E_r). The electrode design problem has thus been twice as difficult as it would be were a separate electrode used to perform each of these functions.

In accordance with my invention, I propose to use a compound or specially designed reflector electrode, which desirably includes, in addition to the reflector member, one disposed between it and the resonant cavity member or adjacent grid, whereby the potential (E_z) of this member may be varied independently, as compared with that (E_r) of the reflector. By applying such a device to a velocity-modulated beam-type generator for electricity of ultra-high frequency, such as a reflex Klystron, for example, desired results are obtained as follows.

An advantage of using such a compound reflector lies, not only in its superior versatility as

compared with a single electrode, but principally and specifically in its ability to control the focusing of the returned electron beam and its transit time, that is, its relative phasing as compared with radio-frequency voltage, independent of each other.

If the potential of the shell or resonant cavity member is regarded as 100 and that of the reflector as 0, then it has been found experimentally that radio frequency power output was obtained from a reflex Klystron, equipped with a compound reflector embodying my invention, when the potential of the associated member, such as an inner cylinder disposed between the reflector and shell, lay in the range between 0 and 19. The equipotential surface at which electrons reached zero velocity before starting back in the opposite direction was in the range between 15 and 35, that is, always positive with respect to the associated member or cylinder.

Thus, the turn-about positions for the electrons in all cases lay in the region defined by the lower half of the control member and adjacent shell end-plate or grid, showing that focusing of the returned beam depends entirely on the potential of said control member relative to the shell potential.

It was found that best results could be obtained, for a given reflector potential, when the inner or control member was kept at a constant potential positive with respect to the reflector cup for all values of shell voltage. This is an important practical advantage for my compound reflector, as for any single mode of operation the compound reflector requires no more adjustment than a single electrode.

Referring now to the drawings in detail, like parts being designated by like reference characters, and first considering the embodiment of my invention illustrated in Figs. 1 and 2, there is shown a portion of a reflex Klystron 11 comprising an electron-emissive cathode 12 supported inside of an envelope portion 13, only fragmentarily illustrated. Said envelope portion has a collar or outstanding annular flange member 14 extending from its periphery, and at one end partly closed by grid support member 15 having a collar 16 providing an opening for the passage of electrons and to which grids 17 and 18 are secured.

The upper portion of the collar 16 defines the interior portion of the cavity resonator or shell member 19, secured thereto by means of a flexible diaphragm or lower wall portion 21. The remainder of the resonator member consists of an opposite or upper wall portion 22 provided with an opening partly closed by a grid portion 23, and connected to the flexible portion 21 by an outer cylindrical or peripheral portion 24, from which, in the present embodiment, projects a coaxial output member or antenna 25. Mechanical tuning or adjustment of the resonant cavity may be effected by turning a plurality of screws 26 to flex the member 21 to a greater or lesser extent, against the resistance of the tension coil springs 27, acting between the flange member 14 and a corresponding flange member 28 to which the upper wall portion 22 and the cylindrical wall portion 24 are secured, as by means of solder 29.

Projecting axially from the flange member 28 is a sleeve member 31 closed at its outer or upper end by a flare member 32, of glass or other vitreous material, through a press 30 of which pass a rod or support 33 for a reflector electrode 34, here shown generally spherical, and

5 one or more leads or supports 35 for electrode means, such as an associated control electrode 36, here shown as hollow cylindrical, which with associated insulating material 37 between it and a generally cylindrical rim portion of said electrode 34, form a compound reflector device or electrode embodying my invention. The insulating material 37 divides the compound reflector electrode into a plurality of insulated zones, the spherical portion of the electrode 34, or second zone, being arcuate about the axis of the opening in the surface of the electrode 36 considered as the first zone. As the diameter of the opening in the control electrode 36 is less than that of the electrode 34, the surface of the compound reflector electrode, subtends about a point in its central region, a solid angle substantially greater than 2π solid radians.

20 When in operation, a beam of electrons from the properly oriented cathode 12 passes successively through the openings, intermediate the electron-beam projecting means 12 and the reflector electrode, left by the grids 17, 18 and 23, and is turned back, before reaching the reflector 34, at the equipotential surface in accordance with the velocity thereof. The equipotential surfaces are not sketched in Fig. 1, but corresponding surfaces 38 and 39 are shown in Fig. 6. An electron having a relatively slow velocity may be reflected at a relatively high potential surface, corresponding, for example, with the one designated as 38, while a relatively fast electron may penetrate such surface and finally be reflected at a surface such as 39, having a more negative potential. In any event, however, the reflector surface will be concave, or of such a character as to reflect all of the electrons back into the shell or resonator device and avoid undesired dispersion thereof.

Fig. 1 also illustrates a wiring diagram which may be used in the operation of the generator. The cathode 12, for example, may be heated by energy from an adjustable transformer 41, the primary winding 42 of which is connected to a suitable source of power 43, and the secondary winding 44 of which is connected to the heating filament 40 of the cathode. The shell or resonant cavity member 19, desirably grounded as indicated at 52, is maintained at a desired high positive potential (E_s) with respect to the cathode 12, as by means of battery 45 or other source of direct current, the adjustability of this potential being indicated by the movable arrow 46. The reflector member 34 is maintained at a negative potential (E_r), with respect to the shell member 19, as well as with respect to the cathode 12, as by means of a battery 47 or other source of direct current, adjustability being indicated by the movable arrow 48. The potential of the control element 36, in this case shown hollow cylindrical, and at a potential positive with respect to the reflector 34, and intermediate that of said reflector and the resonator 19, is controlled in any desired manner, as from the same battery 47 by means of the movable or adjustable means or connecting member 49. The cathode shield 53 is maintained at a relatively small positive potential with respect to the cathode 12 by battery or other source of direct current 54.

In using the Klystron 11 embodying my invention, the "turn-about" equipotential surface is forced deeper into the reflector member 34 by making its potential (E_r) less negative. If the potential (E_s) of the cylindrical control member

36 is kept constant, however, the field lines near its mouth will be essentially unchanged.

Thus I have found experimentally that with the potential difference between the reflector member 34 and the cylindrical member 36 fixed at any one of a number of optimum values, the reflector potential (E_r) for any one of a number of modes in each case remained essentially constant for best output, as the shell voltage (E_s) varied over a wide range. This potential difference, $E_b = E_r - E_s$.

Thus for each value of the inner cylinder voltage (E_s), the compound reflector of the shape depicted in Figs. 1 and 2 can be regarded as a single deep concave reflector, of a corresponding-ly adjusted depth, while having the same mouth diameter and general shape.

The following table shows typical operating data for a reflex Klystron with a compound reflector, as in Figs. 1 and 2.

Shell Voltage E_s	Reflector Cup Potential E_r	Positive Voltage on Inner Cylinder Relative to Reflector Cup E_b	R. F. Output (Milliwatts)
500	-180	50	1.2
600	-180	50	2.4
700	-176	50	2.1
800	-175	50	1.2
900	-175	50	1.0
1,000	-179	50	0.2
500	-205	0	0.9
600	-205	0	3.0
700	-205	0	3.9
800	-205	0	4.0
900	-205	0	4.0
1,000	-205	0	3.2

Another desirable configuration for a compound reflector, corresponding generally with that shown in Fig. 1, is illustrated in Fig. 3, in which the reflector member proper is designated 34^a while the focusing or control member is designated as 36^a, the adjacent grid of the resonant cavity member 19^a being designated as 23^a. The members 34^a and 36^a may be held together by suitable insulation (not shown), as in Fig. 1. In the present instance the reflector member 34^a is not only shaped somewhat differently, but the control member 36^a is hollow frusto-conical rather than cylindrical.

Referring now to the embodiment of my invention illustrated in Fig. 4, the reflector member is here designated by the reference character 34^b, while the associated control member is designated as 36^b, the grid of the associated resonant cavity member 19^b being designated as 23^b. In this case, the reflector member is like a hollow cylinder of short axial length and closed at only one end, while the control member 36^b is like a surface of revolution, somewhat frusto-conical except that it curves longitudinally as well as circumferentially.

The embodiment of my invention illustrated in Fig. 5 involves a reflector member 34^c, somewhat like the reflector 34^a of Fig. 3, and a control electrode 36^c in the form of a flat plate with an opening 51 of a diameter less than that of the mouth of the reflector member 34^c but, like the corresponding openings of the other forms, at least as large as the adjacent resonator opening or grid. The associated resonator is designated by the reference character 19^c, the adjacent grid thereof being 23^c.

In designing single electrode reflectors for reflex Klystrons, the chief consideration has been to obtain the maximum power conversion effi-

ciency in producing radio-frequency oscillations. The result has been, in most commercial models, a shallow cylindrical cup, whose base is given a slightly concave curvature facing the cathode.

- 5 In some Klystrons the radio-frequency power output tends to decrease sharply with slight deviations of the shell or beam-accelerating voltage (E_s) from its optimum value. However, a fairly broad range of shell voltage can be used without sharp decline in power output, providing the reflector voltage (E_r) is readjusted at each successive change in shell voltage. This adjustment of reflector potential to get maximum power output, for any value of shell voltage, is fairly critical.

- 15 It is clearly an improvement, increasing ease of operation and maintenance, if a reflector is used so that one of the two voltages (E_s and E_r) can be varied over a wide range without greatly affecting the radio-frequency power output of the oscillator. An embodiment of such a reflector is illustrated in Fig. 6 and designated by the reference character 34^d. When using such a reflector in a Klystron, as illustrated in Fig. 1, the shell potential may be varied over a range of more than 500 volts with a constant reflector voltage (E_r) with sustained maximum radio-frequency power output.

- 20 This means that, in addition to maintaining good electron-beam focusing over this range of (E_s), the reflector configuration also gave rise to approximately constant transit time for the corresponding range of penetration distances of electrons into the reflector region, with unchanged voltage applied to the reflector.

- 25 The essential features of my reflector, illustrated in Fig. 6 are:

- 30 (1) Cylindrical rim portion close to the outer surface of the adjacent wall of the resonator member (19^d) producing an equipotential field contour of high curvature, as shown by the dotted lines designated 38 and 39, and in terms of electron optics, short focal length.

- 35 (2) The depth of the remaining or generally spherical portion of the reflector cup 34^d is shown approximately as great as the radius of its mouth. The bottom need not be spherical, as illustrated, but can be flat or otherwise formed, its shape having little effect on the equipotential surfaces at which the electrons come to rest and reverse directions, as these surfaces are close to the mouth of the cup, due to the high field concentration there. The depth of the cup is necessary to permit these equipotential surfaces to assume the desired shapes, such that electrons penetrating to desired distances are returned in a beam focused to approximately the same position on the tube axis between the cavity grids.

- 40 Another way of regarding this operation is to consider the reflecting equipotential surface as an electron-optical mirror. Inasmuch as any transverse force acting on an electron changes its direction of motion most greatly when the electron's velocity is least, the electrostatic forces

- 45 acting on the electrons when they come to rest are most important in determining their return path. Thus the equipotential surfaces in the neighborhood of the turn-about position must have focal lengths which are roughly proportional to their distances from the region between the two cavity grids, in order that electrons of a large range of entrance velocities will be returned and refocused at that position. This is the characteristic possessed by a reflector of the shape illustrated in Fig. 6.

Typical data for one such reflector used in a Klystron as illustrated in Fig. 1, is as follows:

Operating data:

Beam current = 15 ma.

Shell Voltage, E _s	Reflector Voltage, E _r	R. F. Power Output (Milliwatts)
500	-250	1.6
600	-250	8.0
700	-250	11.0
800	-250	9.0
900	-248	8.0
1,000	-250	9.0

In general, variations of the shell voltage changes the quality of the radio-frequency output by altering both its magnitude and its frequency. In the former design of Klystron, any change in the shell voltage must be accompanied by a corresponding change in the reflector voltage to maintain approximately constant transit time and so sustain oscillations. By using either the single or compound reflector embodying my invention, both of these variations in output may be effected by changing only one voltage, namely, that of the shell. For example, increasing the shell voltage, increases the frequency, and vice versa.

From the foregoing it will be seen that I have devised a reflector device, which may take either the form of a compound or plural voltage reflector, or that of a single deep reflector, to facilitate the adjustment of the transit time and control the focusing of the electron beam in a generator of ultra-high frequency. The control of amplitude and frequency may be effected by merely varying the shell voltage, once the potentials of the electrode elements have been pre-set for a desired range of operation. In accordance with my invention the precision and flexibility in pre-setting the desired mode of operation may be vastly increased by using a plurality of reflector elements held at different potentials in place of one, to perform individually the two distinct functions previously required of the one.

Although preferred embodiments of my invention have been disclosed, it will be understood that modifications may be made within the spirit and scope of the appended claims.

I claim:

1. A velocity-modulated high-frequency generator of the reflex type comprising an electron-emissive cathode, a cavity resonator adjacent thereto, a reflector electrode toward which the output of said cathode is directed and disposed on the side of said resonator opposite from that of said cathode, electrode means disposed intermediate said reflector electrode and resonator, means including a source of voltage and conductors connected between said source and said resonator, said reflector electrode, and said electrode means, for maintaining said resonator at a high positive potential with respect to said cathode, said reflector electrode at a negative potential with respect to said cathode, and said electrode means at a potential intermediate that of the resonator and said reflector electrode, in order to control the focusing of the electron beam returned by said reflector electrode.

2. A reflex Klystron comprising an electron-emissive cathode, a cavity resonator associated therewith, a reflector electrode disposed on one side of said resonator opposite that of said cathode, said electrode having a reflecting surface shaped generally like a portion of a sphere open-

ing axially of the Klystron, a cylindrical rim portion disposed coaxially therewith, partially closing the mouth thereof, and extending therefrom close to said resonator, for producing an electric field contour of high curvature, lead-in means from said cathode, resonator, reflector electrode, and cylindrical rim portion, and sources of potential connected to said lead-in means for maintaining said cylindrical rim portion positive with respect to said reflector electrode, but still negative with respect to said resonator, in order to control the focusing of the electron-beam returned by said reflector electrode.

3. In an oscillation generator of the reflex type, a cavity resonator having an opening in each of opposite walls, means for projecting a beam of electrons through said openings, a reflector electrode disposed on the side of said resonator opposite to that of said projecting means, formed with a concave generally spherical surface adjacent said resonator and aligned with the openings, and an electrode member, formed hollow for the passage of the electron beam, partially enclosed in said reflector electrode, disposed coaxially of said generator, positioned between and insulated from said reflector electrode and resonator, and having an opening adjacent said resonator at least as large as the adjacent resonator opening.

4. A cavity resonator having a pair of openings in its walls, means for projecting a beam of electrons through said openings and a reflector electrode aligned with said openings and comprising a hollow member having conducting wall portions subdivided into a plurality of insulated zones, said openings being intermediate the means and the reflector electrode, and adjustable means connected to said zones for varying at will independently for each of the zones the relative electrical potentials of said zones and said resonator.

5. A reflector electrode for an oscillation generator of the reflex type comprising a hollow body having a surface of conducting material subdivided into a plurality of zones insulated from each other, and having an opening in the surface of a first one of said zones, a second one of the zones having an inner surface arcuate about the axis of said opening.

6. A cavity resonator having a pair of openings in its walls, means for projecting a beam of electrons through said openings and a reflector electrode aligned with said openings and comprising a hollow member having conducting wall portions subdivided into a plurality of insulated zones, said means being oriented relative to the openings and the electrode to project said beam through the openings toward the reflector electrode, and adjustable means connected to said zones for varying at will the relative electrical potentials of said zones and said resonator, the surface of said reflector electrode subtending, about a point in the central region of said reflector electrode, a solid angle substantially greater than 2π solid radians.

7. In an oscillation generator of the reflex type, a cavity resonator having aligned openings, means for projecting a beam of electrons through said openings, a reflector electrode disposed on the side of said resonator opposite to that of said projecting means, aligned with the openings, and presenting to said resonator a cup-shaped surface, and an electrode member, insulated from, and partially bridging the gap between, said reflector electrode and resonator, formed with an

electron beam passage, at least as large as the adjacent resonator opening, and disposed coaxially of said generator.
